UNITED STATES PATENT OFFICE.

LUDWIG FUCHS, OF LUNDENBURG, AUSTRIA-HUNGARY.

MACHINE FOR WASHING SUGAR.

SPECIFICATION forming part of Letters Patent No. 691,899, dated January 28, 1902.

Application filed June 7, 1899. Serial No. 719,694. (No model.)

To all whom it may concern:

Be it known that I, LUDWIG FUCHS, a subject of the Emperor of Austria-Hungary, residing at Lundenburg, in the Province of 5 Moravia, in the Empire of Austria-Hungary, have invented certain new and useful Improvements in Machines for Washing Sugar; and I do hereby declare the following to be a full, clear, and exact description of the invention, such as will enable others skilled in the art to which it appertains to make and use the same, reference being had to the accompanying drawings, and to letters of reference marked thereon, which form a part of 15 this specification.

This invention has relation to appliances for washing or clearing sugar, and more particularly to that class of appliances comprising a swinging spray-pipe adapted to be 20 swung into and out of the centrifugal and provided with a cut-off device operating to cut off the supply of clairce from the spray-pipe when the latter is swung out of the centrifugal.

25 My invention has for its object means for adjusting the length of the spray-pipe relatively to the height of the basket of the centrifugal.

It has for its further object a peculiar construction of spraying-nozzle and the combination therewith of means whereby the area to be covered by the clairce can be varied within certain limits.

Finally, the invention has for its object the 35 combination, with the swinging spray-pipe, of a peculiar cut-off device.

That my invention may be fully understood, I will describe the same in detail, reference being had to the accompanying drawings, in which—

40 Figures 1 and 2 are fragmentary vertical sections of a centrifugal equipped with my improved washing appliances. Figs. 3 and 4 are fragmentary top plan views of Figs. 1 and 2, respectively, shown partly in section, the spray-pipe being shown as swung out of the centrifugal; and Fig. 5 is a detail sectional view of the outer end of the spray-pipe and its nozzle.

45 On the head of the centrifugal A is arranged a plate α , adjustable toward and from the axial space of said centrifugal by means

of bolts α' , passing from the head of the centrifugal through slots α^2 in said plate and carrying suitable lock-nuts. The plate α has 55 secured thereto or formed integrally therewith a tubular union b , screw-threaded internally at its upper flanged end for the reception of a valve-seat plug b' for a cone-valve v , moving freely in the union b and being provided with guide-ribs v' . To the plug b' is screwed a coupling-sleeve b^2 , by means of which the clairce feed-pipe c is coupled to union b in a well-known manner. The spray-pipe d extends into the coupling b and has 60 an attenuated screw-threaded portion d' fitting the aforesaid internal-screw-threaded portion of union b , the inner end of said attenuated extension lying close to the ribbed stem of valve v , and the pitch of the screw- 65 threads and the travel of the valve v to its seat are so adjusted that when the pipe d is swung around an arc of a circle of about one hundred and eighty degrees in one direction the pipe d will move into union b sufficiently 70 to carry the valve v to its seat in plug b' , and thus cut off communication between the clairce feed-pipe c and said pipe d . On the other hand, when the valve v is seated the portion of greater diameter of pipe d abuts 75 against a shoulder b^3 in tube b , with a view to provide a second cut-off in case of leakage at the valve. The spray-pipe d extends through a flanged sleeve d^2 , by means of which and a coupling-sleeve d^3 it is coupled to the tubular union b , as more particularly shown in 80 Fig. 3.

The spray-pipe d is an angle or L pipe made in two sections screwing into each other, as shown, so that the leg d^5 d^6 may be lengthened 90 or shortened relatively to the height of the mass of sugar in the basket of the centrifugal. Although I prefer the construction described, it is obvious, however, that the spray-pipe d 95 may have formed thereon the casing or barrel of a stop-cock, as shown at d^4 , Fig. 4, and the union-pipe b , constructed in the form of a stop-cock plug having a port leading into said casing and so located relatively to the inlet of pipe d as to be out of register therewith when the said pipe is swung out of the centrifugal, Fig. 4, and in register when swung into the centrifugal, Fig. 2.

In the arrangement shown in Fig. 3 the

valve *f* has free play in cylinder *b* and is of a well-known construction, the arrangement being such that when the spray-pipe *d* is swung out of its operative position, Fig. 1, 5 into the position shown in said Fig. 3 the said pipe *d* will be screwed into cylinder *b* and move the valve *f* to its seat to cut off the clairce from the spray-pipe. When, on the contrary, the spray-pipe is swung into its operative position, Fig. 1, the said pipe is 10 screwed out of cylinder *b* and caused to recede from the valve *f*, the latter being then unseated by the pressure of the clairce in pipe *c*. The nozzle end of the angle-pipe *d* is formed 15 at right angles to the section *d*³, so that when said pipe is swung into the centrifugal the nozzle will face the inner wall thereof. The nozzle portion *k* of pipe *d* has an internal spiral fluid-passage *k'*, and in the otherwise 20 smooth bore of said portion *k* is fitted an internally-screw-threaded sleeve *h*, into which is screwed a conical plug *g*. Onto the nozzle portion *k* of pipe *d* is screwed the spraying-cap *l*, provided in its outer face with a 25 conical axial recess *l'* in communication with a similar recess *l'* in the inner face, concentric with the cone of plug *g*. The spraying-cap *l* has a flange or projection *h'* encompassing the recess *l'* and forming a central fluid-chamber 30 *m* and an encompassing packing-chamber for the reception of a suitable packing-gasket *m'*. Inasmuch as the clairce is fed to the spraying-nozzle under pressure, it acquires a swirling or rotary movement as it 35 flows through the spiral passage *k'* and thence into chamber *m* about the cone of plug *g* and issuing from the cap *l* is converted by the external conical recess *l'* in said cap into a cone. It is obvious that if the diameter of said 40 external recess *l'* is in proper proportion relatively to the height of inner wall of the basket of the centrifugal the cone of spray will cover the entire area of said wall in a vertical direction and a similar area in a horizontal direction, hence a much greater area than could 45 be covered by a perforated spray-pipe. On the other hand, by adjusting the plug *g* nearer to or farther from the outlet-port in cap *l* the volume of clairce sprayed onto the sugar can 50 be varied, while the nozzle can readily be adjusted to the height of the sugar in the basket by screwing the leg member *d*⁶ into or out of the leg member *d*⁵ of spray-pipe *d*, as will be readily understood. Finally, by 55 adjusting the support *a* for the union-pipe *b* toward or from the axis of the centrifugal the nozzle of spray-pipe *d* can be brought nearer to or farther from the inner wall of the basket and the sugar therein, and thereby distribute 60 the clairce over a greater or less area with greater or less force.

Having thus described my invention, what I claim as new therein, and desire to secure by Letters Patent, is—

65 1. The combination with the basket of a centrifugal machine, of a clairce feed-pipe

and a spray-pipe connected therewith to revolve on a horizontal axis and to be turned into and out of said basket, a valve-chamber in the connection between the two pipes, a 70 valve-seat therein, and a valve arranged to be moved off its seat by the pressure of the liquid in the clairce feed-pipe and to be moved to its seat by the spray-pipe when turned out of said basket, substantially as set forth. 75

2. The combination with the feed-pipe *c* and spray-pipe *d* provided with an external screw-thread, of the union *b* provided with a corresponding internal screw-thread, a coupling coupling union *b* to pipe *d* so as to enable the latter to turn freely, a valve-seat plug *b'* screwed into the opposite end of union *b* and coupled to feed-pipe *c* so as to adapt the latter to turn freely and the cone-valve *v*, substantially as and for the purpose set forth. 85

3. The combination with the basket of a centrifugal machine, of a clairce feed-pipe extending over the top of said basket beyond its inner wall, a spray-pipe connected with said feed-pipe to revolve about a horizontal 90 axis, and to swing into and out of the basket, said spray-pipe of such a length as to bring its spraying-nozzle about midway of the inner vertical wall of the basket, said spraying-nozzle organized to distribute the clairce over 95 the full length of the inner wall of said basket, and a valve in the connection of the two pipes adapted to be unseated by pressure in the feed-pipe and to be positively seated by the spray-pipe when turned out of the basket, 100 substantially as set forth.

4. The combination in a machine such as described with the spray-pipe *d*, a sleeve fitted in the outlet thereof, a directing-cone fitted fluid-tight in said sleeve, and a spiral 105 groove between the pipe and sleeve; of a cap secured to said outlet of pipe *d*, said cap having a conical recess in its outer and inner faces concentric with the directing-cone and in communication with each other, and a 110 chamber between said cone and cap in communication with the aforesaid spiral groove.

5. The combination with the basket of a centrifugal machine, of a clairce feed-pipe extending over the top thereof beyond its inner wall and adjustable toward and from the latter, a spray-pipe connected with the inner end of said feed-pipe to be swung into and out of said basket, a valve-seat in said connection and a cut-off valve adapted to be 115 moved from its seat by pressure on the clairce-pipe and to its seat by the spray-pipe when swung out of the basket, for the purpose set forth.

In testimony that I claim the foregoing as 125 my invention I have signed my name in presence of two subscribing witnesses.

LUDWIG FUCHS.
